UNITED STATES PATENT OFFICE.

MILTON D. MESEROLE, OF MILFORD, CONNECTICUT, ASSIGNOR OF ONE-HALF TO
GEORGE M. HAYES, OF NEW HAVEN, CONNECTICUT.

PENCIL SHARPENER.

Application filed February 25, 1925. Serial No. 11,436.

To all whom it may concern:

Be it known that I, MILTON D. MESEROLE, a citizen of the United States, residing at Milford, in the county of New Haven and 5 State of Connecticut, have invented a new and useful Improvement in Pencil Sharpeners; and I do hereby declare the following, when taken in connection with the accompanying drawings and the characters of 10 reference marked thereon, to be a full, clear, and exact description of the same, and which said drawings constitute part of this application, and represent, in—

Fig. 1, a side view of a pencil sharpener 15 constructed in accordance with my invention.

Fig. 2, a front view of the same.

Fig. 3, a sectional view on the line 3—3 of Fig. 1.

20 Fig. 4, a vertical, sectional view of the housing with the cutter and cutter-frame removed.

Fig. 5, a sectional view of the cutter and 25 cutter-frame detached.

Fig. 6, a side view, partly in section, showing modified means for interlocking the cutter-frame with the housing.

This invention relates to improvement in 30 pencil sharpeners, particularly to sharpeners which comprise a conical, pencil-tip-receiving recess formed with a slot having a blade arranged to enter said slot, and especially to 35 pencil sharpeners having cutters of this type mounted in a sheet-metal casing. The object of this invention is to provide a pencil 40 sharpener of the type referred to, which shall be enclosed in a sheet-metal housing, which will facilitate the ready withdrawal of the cutter from the housing and permit the ready replacement of cutting blades and 45 provide an effective pencil sharpener which may be produced at a very low cost for manufacture, and the invention consists in the construction as hereinafter described and particularly recited in the claims.

In carrying out my invention, I employ 50 a cutter 10 of substantially usual form, with a tapered recess 11 for the reception of the end of a pencil to be sharpened. This cutter is formed with a longitudinal slot 12, and attached to the cutter by a screw 13 is a blade 14, the edge of which extends into the chamber 11. The inner end of the cutter is formed with a tubular bearing 15, and 55 at the outer end with a stud 16. The bear-

ing 15 and stud 16 are mounted in opposite ends of a U-shaped bearing-piece 17, struck up from sheet-metal, and fixed to the outer end of the stud 16 is a crank 19. The cutter-support is formed with side-walls 20 and 21, which, with the ends 17 and 18, form a box to receive the cuttings from a pencil. This box, with its cutter, is mounted in a housing 22, also formed from a strip of sheet-metal bent into U-shape, 60 with the edges 23 turned outward to form flanges by which the housing may be secured to a support. Extending transversely across the housing is a floor 24 forming a chamber for the reception of the cutting mechanism, this housing being closed at the back by a wall 25 formed with a clearance-opening 26 for the bearing 15. Preferably, the outer edge of the floor, on opposite sides of the center, will be formed 65 with lips 27 for the reception of the lower edge of the front-wall 18, which may be conveniently lifted into the lips 27 by means of a finger-piece 28. Instead of interlocking the cutting mechanism with the housing by means of the lips 27, the finger-piece 28 may be formed with a depression 29 to set over a nub 30 struck downward from the floor 24, as shown in Fig. 6 of the drawings, whereby the cutting mechanism will 70 be interlocked with the housing. I, therefore, do not wish to be understood as limiting the invention to any particular means for securing the cutting mechanism in the housing. 75

A pencil sharpener thus constructed and shown may be produced at very low cost for manufacture, and the cutting mechanism may be readily removed from the housing 80 to empty cuttings and facilitate the removal 85 and replacement of the cutting blade.

I claim:

1. A pencil sharpener, comprising a cutter-frame formed from sheet-metal, and 100 comprising front and rear walls, a conical cutter mounted in said walls and provided with a crank, a housing for the reception of said cutter-frame, said housing comprising a floor upon which the cutter-frame rests and a rear wall against which the cutter-frame extends, and means for detachably interlocking the cutter-frame with the housing. 105

2. A pencil sharpener, comprising a cutter-frame formed from sheet-metal, and 110

comprising front and rear walls, a conical cutter mounted in said walls and provided with a crank, a housing for the reception of said cutter-frame, said housing comprising a floor upon which the cutter-frame rests and a rear wall against which the cutter-frame extends, the forward edge of the said floor formed with lips with which the lower edge of the cutter-frame may engage, whereby the cutter-frame is detachably locked in the housing.

3. A pencil sharpener, comprising a cutter-frame having a bottom, sides, and ends extending above the sides, a cutter mounted in said ends and provided with a crank-

handle, a housing formed from a strip of sheet-metal bent into U-shape and provided with a floor upon which the cutter-frame rests and a rear wall, the said wall having a clearance opening for one end of the cutter, said frame adapted to be entered into the said housing.

In testimony whereof, I have signed this specification in the presence of two subscribing witnesses.

MILTON D. MESEROLE.
